Harry Finer, Wilmington, Mass.

Application March 20, 1941, Serial No. 99,729

Term of patent 3½ years

To all whom it may concern:

Be it known that I, Harry Finer, a citizen of the United States of America, residing in Wilmington, county of Middlesex, and State of Massachusetts, have invented a new, original, and ornamental Design for a Dress, of which the following is a specification, reference being had to the accompanying drawing, forming part thereof.

Fig. 1 is a front view of a dress showing my new design.

The characteristic feature of my design resides in the combination on the specific two-toned dress disclosed of the specific embroidered motif on the blouse thereof in association with the tucking below the narrow shoulder yokes and the three tucks on each side of the front opening at the waistline, all as shown.

I claim:

The ornamental design for a dress, as shown, and described.
